ATTORNEY.

UNITED STATES PATENT OFFICE.

JOHN S. POTTER, OF NEWTON, MASSACHUSETTS.

ELECTRIC CUT-OUT.

SPECIFICATION forming part of Letters Patent No. 445,253, dated January 27, 1891.

Application filed August 16, 1890. Serial No. 362,196. (No model.)

To all whom it may concern:

Be it known that I, JOHN S. POTTER, a citizen of the United States, and a resident of Newton, in the county of Middlesex and State of Massachusetts, have invented new and useful Improvements in Electric Cut-Outs, of which the following, taken in connection with the accompanying drawings, is a specification.

This invention relates to improvements in electric cut-outs for incandescent-lamp wires or other electrical devices, and it is carried out as follows, reference being had to the accompanying drawings, wherein—

Figure 1 represents a top plan view of the invention. Fig. 2 represents a longitudinal section on the line X X shown in Fig. 1. Fig. 3 represents an end elevation. Fig. 4 represents a detail plan view of the detachable binder-plate and its insulator, and Fig. 5 represents a cross-section on the line Y Y shown in Fig. 4.

Similar letters refer to similar parts wherever they occur on the different parts of the drawings.

The device consists of an insulating-base A, preferably made of porcelain or suitable non-conducting material, said base having on its upper surface ridges or projections A' A' A', between which the series of cut-outs are arranged. Each of such cut-outs consists of a screw-threaded metal shell B, containing in its lower end a lozenge or disk C, made of porcelain or suitable non-conducting material, as shown in Fig. 2. In one piece with said shell B, or metallically connected thereto, is a metal binder-plate B', which is secured to the base A by means of a screw B'' passing through a perforation in the base A and screwed into the said binder-plate, as shown in Fig. 2.

B' is a binder-screw screwed to the binder-plate B' for the purpose of attaching to said binder-plate the line-wire D, as usual.

b' is a detachable binder-plate secured to the base A by means of a screw b'' passing through a perforation in the base A and screwed into the binder-plate b', as shown in Fig. 2.

b' is a binder-screw screwed to the binder-plate b' for the purpose of securing to it the line-wire D'.

The inner end of the binder-plate b' projects through a side opening in the shell B and is preferably supported on the lozenge or disk C. For the purpose of preventing metallic contact between the detachable binder-plate b' and the shell B, where said binder-plate passes through the said shell, I arrange between said parts an insulating-block b, made of porcelain or other suitable non-conducting material, by means of which the current from the wire D' and binder-plate b' is prevented from going through the shell B without first passing through the fusible-plug device, such fusible-plug device consisting, as usual, of a hollow glass (or insulating material) plug E, surrounded by a screw-threaded metal band or ring E', adapted to be screwed into the metal shell B. In a perforation in the bottom of the hollowed plug E is inserted a metal button E'', which is held in metallic connection with the inner end of the binder-plate b'.

e is a fusible wire, one end of which is connected to the button E'', and having its other end connected to the screw-threaded ring E', as shown in Fig. 2.

E³ is a cap or protector secured to the upper end of the plug E, as usual.

The current passes normally from the wire D' to the binder-plate b', and from it, through the button E'', fusible wire e, metal ring E', and metal shell B, to the binder-plate B' and wire D. If an abnormal or dangerous current is communicated to the wire D', the wire e is fused and the wire D cut out from the wire D', or vice versa, thus preventing such dangerous or abnormal current from being communicated to the lamps, their connections, or the building in which they are located.

If it were not for the interposition of the insulating-block b between the binder-plate b' and metal shell B, accumulations of dirt, dust, and moisture within and around such shell would cause electrical connection at all times between the wires D' and D, thereby preventing a dangerous current from being cut out from between the wires. In devices of this kind a non-conducting material placed between the binder-plate b' and shell B, as above described, is of the utmost importance.

On the under side of the base A, I make a

series of parallel ribs A" A", as shown in Fig. 3, between the series of cut-outs, for the purpose of preventing moisture from the walls or ceilings, to which the base A is secured, 5 from making electrical connection between the respective wires attached to the individual cut-outs. By this arrangement air spaces or channels A³ A³ are produced directly below the places where the cut-outs and their fasten-
10 ing-screws are located, preventing entirely any communication produced by moisture between the respective line-wires and their cut-outs.

Having thus fully described the nature, 15 construction, and operation of my invention, I wish to secure by Letters Patent and claim—

In an electric cut-out, an insulating-base

and a metal shell having a metallically-connected binder-plate and an insulating-disk at its bottom, combined with a detachable binder-plate and an insulating-block arranged between such binder-plate and shell, and a fusible wire metallically connected to such insulated binder-plate and shell, substantially as and for the purpose set forth. 20 25

In testimony whereof I have signed my name to this specification, in the presence of two subscribing witnesses, on this 11th day of August, A. D. 1890.

JOHN S. POTTER.
